JOHN W. BAKER, OF PARKERSBURG, WEST VIRGINIA.

Letters Patent No. 69,155, dated September 24, 1867.

IMPROVEMENT IN HYDRANTS.

The Schedule referred to in these Letters Patent and making part of the same.

TO ALL WHOM IT MAY CONCERN:

Be it known that I, JOHN W. BAKER, of Parkersburg, in the county of Wood, and State of West Virginia, have invented a certain new and useful Improvement in Hydrants; of which improvement the following is a full, clear, and exact description, reference being made to the accompanying drawing, which makes part of this specification, and which represents a vertical longitudinal section through a hydrant embodying my said improvement.

It is the object of my invention to obviate the difficulties and inconveniences occasioned by the freezing and bursting of the supply pipes of hydrants; and to this end my invention consists in shutting off the water directly at the main, and draining the hydrant pipe so that it is emptied, and remains empty, until the water is again turned on from the main.

The service pipe B is tapped into the main in the usual manner, and so that it may slightly incline upwards from the main to the elbow-joint, and is supported in a proper casing for its necessary protection. As near the main as practicable I fit into the supply pipe a two-way cock, A, upon the head of which is a link, C, attached to a link-rod, D, and connected with a hand-lever, E, passing up through the casing F, and working back and forth through a slot in the top of the casing.

The drawing shows in black lines the position of the parts when the valve is closed, and the red lines their position when it is open. When the water is turned on, the waste-way *i* is closed, and no water escapes through it; but when the water is shut off at the main the waste-way *i* in the cock A leads from the pipe B into the waste-way I, and the water is thus drained from the hydrant, and escapes into the earth, this draining being facilitated by the inclination of the pipe towards the main.

By this means any freezing in the pipe is effectually prevented.

What I claim herein as my invention, and desire to secure by Letters Patent, is—

1. The arrangement, as described, of the shut-off cock and waste-way immediately at the main, for the purpose set forth.
2. The combination, substantially as described, of the shut-off cock and waste-way at the main with the hand-lever and connecting-rod, for the purpose set forth.
3. The combination with the inclined supply pipe of the shut-off cock and waste-ways *i* I, immediately at the main, for the purpose set forth.

In testimony whereof I have hereunto subscribed my name.

JOHN W. BAKER.
